UNITED STATES PATENT OFFICE.

ALEXANDER S. KAZIMER, OF FISHKILL-ON-THE-HUDSON, NEW YORK.

METALLIC RAIL-TIE.

No. 899,990.

Specification of Letters Patent.

Patented Sept. 29, 1908.

Application filed October 12, 1907. Serial No. 397,144.

To all whom it may concern:

Be it known that I, ALEXANDER S. KAZIMER, a citizen of the United States, residing at Fishkill-on-the-Hudson, in the 5 county of Dutchess and State of New York, have invented new and useful Improvements in Metallic Rail-Ties, which the following is a specification.

This invention relates to improvements in 10 railway ties and means for securing the rails on the ties, and the said invention consists in the construction, combination and arrangement of devices hereinafter described and claimed.

15 One object of this invention is to effect improvements in the construction of the tie.

A further object is to provide improved 20 means for securing the rails on the tie so that the rails can not be loosened by malicious persons for the purpose of wrecking a train.

In the accompanying drawings:—Figure 1 is a plan of a portion of a railway track equipped with my improved ties and rail securing devices. Fig. 2 is a vertical longitudinal sectional view of one of my improved ties, showing the rail securing devices in elevation. Fig. 3 is a side elevation of the tie, the rails being indicated in cross section. 30 Fig. 4 is a detail end elevation of the tie, showing a portion of a rail thereon. Fig. 5 is a horizontal longitudinal sectional view of the tie. Fig. 6 is a detail transverse sectional view of the same.

35 My improved tie 1 comprises a body or base portion 2 and a cover plate 15. The body or base portion may be a casting or a pressed steel plate, is hollow, open at the ends and top, and comprises a bottom 3 inclined upwardly converging sides 4 and flanges 5 which extend outwardly over the upper edges of said inclined sides. The bottom 3 is concavo-convex, cross sectionally with the convex side innermost, so that a hollow is formed under the body of the tie which 45 enables the tie to be the more effectually seated on the road bed. At the ends of the body of the tie are doors or closure plates 6 the lower sides of which are hinged to the bottom of the tie as at 7. Cross bars 8, which 50 are preferably of the form shown in Fig. 5, but which may be of any suitable construction, are placed in the body of the tie between the sides and near the ends thereof and are secured to the said sides, as at 9.

Each side of the tie is provided at a suitable distance from one end with an opening 10 and with a closure plate 11, the said closure plates being on the inner side of the body of the tie, slidable in guide-ways 12 so that they may be moved to open or close said openings 10 and the said closure plates 11 are provided with outwardly extending rods 13 which pass through guide openings in the cross bars 8 and are detachably secured at 65 their outer ends as at 14 to the sides of the tie body at points near the ends thereof.

The top plate 15 which covers the tie is secured by rivets or other suitable fastening devices 16 on the flanges 5. The doors or 70 closure plates 6 at the ends of the tie, when closed are secured to the ends of the said plate 15 by means of bolts 17 or other suitable devices. The said plate 15 is provided near its ends with openings 18.

75 On the under side of the plate 15 are inner plates 19 and on the upper side of said plate 15 are base plates 20 on which the rails, indicated at *a* bear. Said plates 19 and 20 are respectively provided with openings 21—22. 80 Rail securing arms 23 extend through the openings 21, 18 and 22 and are pivotally mounted in the opening 21 of the inner plates 19 as at 24. The said rail securing arms are formed at their upper end with 85 hooks 25 to engage opposite sides of the rail base flanges as shown in Fig. 2. The rail securing arms 23 are respectively connected to the cross bars 8 by rods 26 which are pivotally connected as at 27 to the lower ends of 90 the said rail securing arms, and the outer ends of which are threaded, extend through the openings in the said cross bars 8 and are provided with adjusting and securing nuts 28. It will be understood that by tightening the said nuts the said rods may be moved longitudinally in the required direction to cause the arms 23 to securely engage their hooks 25 with the rail base flanges and effectually secure the rails on the base plates 20. 95

100 It will be understood from the foregoing description and by reference to the drawings that the lower portions of the rail securing arms and the adjusting rods which enable them to be engaged with and detached from the rail base flanges are entirely concealed in and protected by the tie so that only the upper, hooked ends of the rail securing arms are visible and accessible and, hence, access must be attained to the interior of the tie 110

before the rail securing arms can be detached from the rails. The closure plates 6 which are secured as hereinbefore stated, prevent access to the interior of the tie and plates 11 5 also perform the same office so that wreckers in order to tamper with or take up a portion of a track must break open the ties before they can release the rail securing arms from the rails, and this is so laborious an operation 10 and requires so much time as to render the detection of such an attempt at wrecking a train practically certain.

To further hinder an attempt to remove or 15 displace the rails, I provide the base plates 20 on which the rails rest with upstanding flanges 29 which bear against the outer sides of the rail base flanges so the rails are snugly seated between said flanges 20 and can not be laterally moved until after they have first 20 been raised sufficiently to clear such flanges 29. Therefore, in order to remove a rail it must first be entirely disconnected from the ties at the ends thereof and all of the rail securing arms 23 of the various ties on which 25 such rail rests must be released from such rail. To prevent the rails from being inclined outwardly in an effort to wreck or 30 derail a train, I provide the inner flanges 29 of certain of the base plates with outwardly 35 extending portions 30 to bear on the upper sides of the inner rail base flanges, as shown in Figs. 1, 2 and 3. The closure plates 6 enable access to be attained by authorized 40 persons to the ends of the adjusting rods 26 so that the nuts may be adjusted thereon and the closure plates 11 when the same have been moved to the required position to uncover the opening 10 enable authorized persons to have access to the rail securing arms 45 for the purpose of removing and renewing them in the event they become worn or broken. Hence, the ties with all of their appurtenances can be kept in proper condition without the necessity of removing the ties 50 from the road bed or of removing the cover of the plates from the ties.

Having thus described the invention, what is claimed, is:—

1. A hollow railway tie having openings in its upper side, openings in its sides, and openings in its ends, closures for said side openings, means on the inner side of the tie to secure said side closures, and closures for said end openings, pivotally mounted rail-securing arms having their lower and major portions disposed in said hollow tie and their upper ends extended through the openings in the upper side of said tie and provided with means to engage the base flanges of a rail and means located within the hollow tie to adjust and 60 secure said rail-securing arms, the openings in the sides of the tie enabling access to be obtained to such adjusting and securing means and the closures in the ends of the tie enabling access to be obtained to the means 65 for securing the closures for the side openings.

2. A railway tie having a cover portion, a base plate on such cover portion, such cover portion and such base plate having openings, rail securing arms pivotally connected to such cover portion and having hooks at their upper ends to engage the base flanges of a rail, such rail securing arms extending through the openings in the cover portion 75 and base plate, and means to secure such arms in engaged position.

3. A hollow railway tie having openings in its upper side, pivotally mounted rail securing arms having their lower and major portions disposed in said hollow tie and their upper ends extended through said openings and provided with means to engage the base flanges of a rail, and means located within the hollow tie to adjust and 80 secure such rail securing arms.

In testimony whereof I affix my signature in presence of two witnesses.

ALEXANDER S. KAZIMER.
